UNITED STATES PATENT OFFICE.

LEVI C. KENTON, OF CHATTANOOGA, TENNESSEE.

SHOE.

1,407,661.

Specification of Letters Patent. Patented Feb. 21, 1922.

Application filed December 9, 1920. Serial No. 429,527.

To all whom it may concern:

Be it known that I, LEVI C. KENTON, a citizen of the United States, and a resident of Chattanooga, in the county of Hamilton and State of Tennessee, have invented a new and Improved Shoe, of which the following is a full, clear, and exact description.

This invention has special reference to improvements in shoes and more particularly to those adapted for children's use, although it is here explained that shoes made in accordance with my invention may be made in various sizes as shall be found desirable and necessary without in any way departing from the spirit of the invention.

More particularly, the invention relates to improvements in shoes of the blucher type and style having a double tip and vamp portion to provide a smooth interior surface such as to obviate the necessity of providing a lining for the shoe and particularly at the forward part, so that the lining may only be disposed in the top or quarter part of the shoe and thus have all the appearances of a drill or cotton lined shoe.

A still further and more important object of the invention is to improve shoes of the blucher type set forth in which instead of constructing the shoes of three or more pieces of leather and connecting the front edges of the quarters or top to the rear edges of the vamp by a seam extending between the shank and instep, said parts are formed from two pieces with an additional vamp and toe section thereover, cut in a novel manner to form the lacing flaps and to facilitate the securing of a tongue of novel shape in position by a continuous row of stitching connecting the top part of the double vamp and tip forming the lower part of the shoe to the under part on either side and over the throat portion of the vamp in such a manner as to additionally secure the tongue in position so that the strength of the shoe at this point is equal to the strength of the leather or material from which the shoe is constructed rather than simply being strong as the stitches in the usual manner of securing a tongue in position.

A still further object of the invention in a shoe of the style set forth is to provide a tongue of novel design which is adapted to fit in cut-out portions of the quarters adjacent to the vamp in such a manner as to provide a smooth interior surface at this

point, to doubly secure the tongue to the quarters and vamp, as well as to simultaneously attach the flaps to the shoe at the parts which are cut away to provide a vacancy for receiving the tongue and thus reinforcing the flaps at their point of attachment in such a manner as to prevent the flaps from ripping open or tearing apart from the vamp and other parts to which they are secured.

With the above and other objects in view, the invention resides in the peculiar combination and arrangement of parts to be hereinafter more fully described, illustrated and claimed.

Reference is to be had to the accompanying drawings forming a part of this specification, in which similar characters of reference indicate corresponding parts in all the views, and in which—

Figure 1 is a plan view of a blank forming one of the sides of the shoe;

Figure 2 is a plan view showing the sides over-seamed down the front and a tongue secured in cut-out portions of the sides;

Figure 3 is a plan view of a combined toe and vamp section forming the front portion of the shoe;

Figure 4 is a plan view of an improved tongue forming part of the shoe;

Figure 5 is an under side view similar to Figure 2 to more particularly illustrate the manner of securing the tongue in position;

Figure 6 is a view similar to Figure 2 but showing one of the lacing flaps turned back to illustrate the manner in which the combined toe and vamp section is secured in position;

Figure 7 is a fragmentary under side view showing the manner of securing the tongue to the sides and combination toe and vamp section, the tongue being broken away at one side to show the manner in which it is accommodated by a vacancy formed by cut-out portions of the sides;

Figure 8 is a sectional perspective view of a portion of the complete shoe, the section being taken transversely of the vamp or combination toe and vamp section adjacent to the lacing flaps;

Figure 9 is a sectional view taken on the line 9—9 of Figure 5.

As shown in the drawings, the improved shoe embodies a pair of sides 10, the same, in contra-distinction to the usual quarters or top sections of blucher shoes which have

front edges connected to the rear edges of the vamp by a seam extending between the shank and instep, forming the quarters or tops 11 and extending beyond the shank 12 to provide toe and vamp sections 13 with straight edges 14 down the front. These straight edges are stitched together or overseamed as shown at 15, as are the back edge positions 16, the seams being exposed but 10 the edges of the co-acting parts being butted or brought together edge to edge so as to provide smooth seams interiorly and exteriorly. The sides 10 in rear of the vamp portion are severed inwardly at right angles, 15 as shown at 17, then longitudinally as shown at 18 and outwardly for a short distance as shown at 19, the angular severed portions producing outward extensions 20 at the lower ends of the lacing flaps 21 for a purpose to be hereinafter more clearly made apparent. The edge of the flap adjacent to the inward line of separation or severed portion 17 is preferably rounded as shown at 22 to facilitate the sewing operation as will be 20 hereinafter explained, and to obviate sharp projections likely to catch in objects and tend to tear the flap portions of the sides of the shoe.

It will be observed that by securing the 30 sides together as described and severing the same to produce the extensions of the lacing flaps, the co-acting severed portions produce an intermediate space or vacancy 23 which is left uncovered by such extensions 35 when the latter are turned upwardly and reinforced by facing strips 24 which are secured to the inner face thereof or along the edges of the side forming such flaps, for the attachment of the shoe eyelets and lacing studs. Besides the parts 20 being turned 40 outward to leave the space or vacancy 23 communicating with the opposite sides, such parts or extensions produce a shoe of the blucher style. The tongue 25 which may be 45 made in the bellows form or any other desired form or shape is in the present instance employed to fill the space or vacancy 23 so as to provide a smooth interior surface, strengthen the shoe at this point and avoid 50 the disadvantage of added thickness likely to hurt or injure the foot, as in the ordinary blucher styles of shoes, and for this purpose the tongue is provided at its small or lower end where attached to the vamp with side 55 extensions 26 producing a part or enlargement which conforms to the shape of the vacancy or space 23 in which it is fitted by butting the forward and side edges together and stitching or overseaming said 60 parts, as shown at 27. The extensions 26 are severed from the tongue proper for portions of their lengths, as shown at 28, so as to leave the tongue free as far as the intermediate tongue or stub 29 of a vamp section 65 30. This vamp has side extensions or over-

laps 31 which are stitched to the sides 10 in the manner in which ordinary vamps are secured to the uppers or quarters, as shown at 32, except that in the present instance the vamp is fitted over the front portions of 70 said sides and due to the incisions or cuts 19, the extensions 20 can be bent backward beyond the rearwardly extending ends of overlaps 31 so as to permit the vamp or upper part of the shoe front to be sewed to the 75 sides at the shank portion by a continuous row of stitching or seam 32 passing over one side, over the filled vacancy upward along the curved throat portion of the vamp forming the intermediate tongue or stub portion 29 and 80 then over the other side of the vamp, this stitching simultaneously passing through the extensions 26 substantially centrally and longitudinally of the latter, as shown at 33, across the crotch portions of the cuts or severed portions 28 and through the tongue at the 85 edge of the curved throat portion or stub 29. In this manner the tongue is doubly secured in position in addition to providing a smooth interior surface by butting the front and 90 side edges together as described, while the rear edges of the extensions 26 are beveled, as shown at 34, to overlie the inner portions of the sides adjacent to the severed portions 19 to further insure a smooth interior 95 surface. The beveled portions 34 are held toward the sides by the row of stitching or seam 32 and the row of stitching 35 serving to secure the facing or lining strips 24 to the lacing flaps and thus also reinforce the 100 shoe at the points where the extensions 20 are severed therefrom but which the vamp 30 is positioned over.

The edges of the extensions 20 at the severed portions 18 are secured to the vamp 105 on the outside in interlocking relation to the latter by rows of stitching additional to the rows of stitching 32, as shown at 36, the edges of the facing strips 24 being beveled, as shown at 37, and simultaneously stitched 110 to the vamp 30 to add further reinforcement without unnecessarily increasing the thickness of the parts at these points. The front portions of the sides 10 beneath the vamp section 20 may be split or skived thin or 115 light as desired in any shoe of this design so as to obviate unnecessary thickness at the vamp and toe without weakening the shoe.

Novelty is claimed for the manner of cutting the sides 10 for producing the blucher 120 style of shoe by turning the parts 20 outward and permitting the vamp to be sewed in position by rows of stitching forming a continuous seam in such a manner as to strengthen the shoe at the lacing flaps and 125 to obviate separate stitching of the vamp to the sides or quarters and of the tongue to the curved throat portion of the vamp forming the intermediate tongue or stub 29. The methods of attaching the lacing flaps to the 130

vamp and of securing the tongue in position and in filling the vacancy cut out to provide the extensions of the flaps, are claimed as novel in combination or separately, and it is 5 here explained that in lasting the shoe the shoe the uppers are seamed down the back and reinforced in the usual manner as now commonly done, then if desired the tip of the shoe over the vamp 30 may be provided with 10 a decorative toe or simply stitched to indicate an ordinary ornamental tip. In addition, the shoe may be lined in the top or quarter part thereof and thus have all the 15 appearance of a drill or cotton lined shoe and avoid wrinkles and loose lining in the fore part of the shoe, although it is preferably, due to the smooth interior surface provided by the construction set forth, that the shoe be not lined. Furthermore, by constructing a 20 shoe as specified the strain of the lasting is taken off of the vamp seam and reinforcement is particularly effected at these points due to the manner of securing the tongue in position and the particular way of forming 25 the blucher style of shoe by the extensions at the lower part of the lacing flaps and the method of attachment of these flaps through the rearward extensions of the vamp and tongue respectively. It is also claimed 30 that a shoe made in accordance with the present construction will possess double the useful life of an ordinary shoe and will not change its shape in wearing but will retain it throughout repeated repairs.

35 Having thus described my invention, what I claim as new and desire to secure by Letters Patent is:—

1. A shoe of the blucher type, comprising side portions having extensions stamped therefrom to provide recesses, said sides being secured together to bring said recesses into alignment, a tongue having one end fitted in the aligned recesses and secured to the sides, and a vamp fitted over the front 45 portions of the sides and having the extensions secured over the same.

2. A shoe of the class described, having an upper provided with ends projecting forward to the toe and having angular incisions in its inner edges producing lacing flaps with outwardly extending forward portions, and a toe vamp extending to the sole about the entire part of the shoe forward of the shank thereof, covering said entire portion of the upper and having side extensions to which said outwardly extending portions are secured, said vamp being secured to the forwardly projecting ends of the upper by a continuous line of stitching, and a tongue 60 secured to the vamp and upper.

3. A shoe of the class described, having an upper provided with ends projecting forward to the toe and having angular incisions in its inner edges producing lacing flaps 65 with outwardly extending forward portions,

a toe vamp extending to the sole about the entire part of the shoe forward of the shank thereof covering said entire portion of the upper and having side extensions to which said outwardly extending portions are secured, said vamp being secured to the forwardly projecting ends of the upper by a continuous line of stitching, said angular cut-out portions of the upper producing a vacancy centrally thereof, and a tongue having lateral extensions at its lower end to fit said vacancy, said tongue, vamp and upper being secured together. 70 75

4. A shoe comprising a pair of side portions forming the quarters and extending forward to the toe of the shoe over-seamed along their forward and rear edges with their ends butted together, said sides having severed portions produced by a cut extending inwardly, upwardly and then outwardly, producing movable extensions, vamp sections secured over the forward portions of said sides and at the shank thereof and having an intermediate stub, said extensions interlocking with respect to the vamp through the instrumentality of said outwardly severed portions and stitched thereto to provide lacing flaps, and a tongue separate from the vamp and secured to the stub thereof. 80 85 90

5. A shoe comprising a pair of side portions forming the quarters and extending forward to the toe of the shoe over-seamed along their forward and rear edges with their ends butted together, said sides having severed portions produced by a cut extending inwardly, upwardly and then outwardly, producing movable extensions, vamp sections secured over the forward portions of said sides and at the shank thereof and having an intermediate stub, said extensions interlocking with respect to the vamp through the instrumentality of said outwardly severed portions and stitched thereto to provide lacing flaps, said severed portions producing opposite recesses in alignment when the extensions are bent outwardly and secured to the shank portions of the vamp, lining strips secured to the inner faces of the lacing flaps and having outer extensions secured to the vamp by a single means, and a tongue secured to the forward portions of the sides and to said vamp. 100 105 110 115

6. A shoe comprising a pair of side portions forming the quarters and extending forward to the toe of the shoe over-seamed along their forward and rear edges with their ends butted together, said sides having severed portions produced by a cut extending inwardly, upwardly and then outwardly, producing movable extensions, vamp sections secured over the forward portions of said sides and at the shank thereof and having an intermediate stub, said extensions interlocking with respect to the 120 125 130

vamp through the instrumentality of said outwardly severed portions and stitched thereto to provide lacing flaps, the co-acting spaces produced by the severed portions 5 forming the extensions of the lacing flaps opening between the flaps and underlying a portion of the vamp, and a tongue having lateral extensions providing an enlargement fitted in said vacancy and over-seamed to the 10 sides, said lateral extensions being severed beyond the vamp and the vamp being secured to the sides at the shank portions and throat to simultaneously connect the tongue and extensions thereof to the vamp, and the vamp 15 and side portions to each other.

7. A shoe of the blucher style, including separate side portions forming the uppers and extending forwardly to the toe, said side portions being secured together down the 20 front and at their back edges to provide smooth joints, said side portions being severed at their inner edges to provide extensions having their inner ends free to be bent outwardly, a vamp secured to the 25 shank portions of the sides beyond said extensions when the latter are so bent, and a tongue to which said vamp and shank portions are attached by a single means.

8. A shoe of the blucher style, including 30 separate side portions forming the uppers and extending forwardly to the toe, said side portions being secured together down the front and at their back edges to provide smooth joints, said side portions being

severed at their inner edges to provide extensions having their inner ends free to be bent outwardly, a vamp secured to the shank portions of the sides beyond said extensions when the latter are so bent, the opposed edges of the sides adjacent said 40 severed portions having co-acting recesses, said vamp having a curved throat portion and adjacent rearward extensions partly overlying the vacancy produced by said severed portions, a tongue having partly 45 severed side extensions and fitted within said vacancy with the forward and side edges butting and over-seamed thereto, the rear edges being beveled and a continuous row of stitching connecting the shank portions of the back to the shank portions of the sides, connecting the vamp and extensions of the tongue and also the tongue to the curved portion of the vamp, said stitching intercepting the crotched portions of the 50 cuts separating the lateral extensions from the tongue and the extensions of the flaps being secured to the vamp section and lateral extensions independently of the first named stitching.

In testimony whereof I have signed my name to this specification in the presence of two subscribing witnesses.
